UNITED STATES PATENT OFFICE.

FREDERICK D. RITTER, OF CORUNNA, MICHIGAN, ASSIGNOR TO WEATHERPROOF BODY CORPORATION, OF CORUNNA, MICHIGAN, A CORPORATION OF MICHIGAN.

DOOR AND CURTAIN.

Application filed November 9, 1925. Serial No. 67,839.

This invention relates to the construction of truck cabs and particularly to the doors thereof, and its object is to provide a lower swinging door and an upper sliding curtain adapted to be pulled down onto the swinging door, the swinging door being provided with a beveled upper edge to cause rain to flow outwardly and the lower edge of the curtain permitting the door to be opened and closed without injury to the lower edge of the curtain.

This invention consists in a door hinged to close the lower portion of a door opening and having its upper edge sloping downwardly outwardly and a curtain slideable up and down in the upper portion of the opening and adapted to contact with the upper edge of the hinged door outwardly of the inner or higher part of its top edge, the lower edge of the curtain constituting a yieldable and resilient weatherstrip which permits said higher part of the swinging door to pass freely without injury to the weatherstrip.

It also consists of the details of construction illustrated in the accompanying drawing and particularly pointed out in the claims.

In the accompanying drawing, Fig. 1 is a partial side elevation of the cab of a motor vehicle embodying my present invention. Figs. 2, 3 and 4 are sections on the lines 2—2, 3—3 and 4—4 of Fig. 1, respectively. Fig. 5 is a section similar to Fig. 4 with the relative positions of the parts slightly changed and a slightly different weatherstrip. Fig. 6 is a section of the lower edge of a cab curtain. Fig. 7 is a perspective of a weatherstrip.

Similar reference characters refer to like parts throughout the several views.

Drivers of motor trucks prefer the lower parts of the door openings to be closed while the trucks are in motion and the upper parts open excepting in inclement weather. I have found that this lower portion need not be as wide as the upper portion and have therefore designed a cab whose side 1 has a door opening of two parts, a lower portion 2 in which the door 4 is hinged and an upper portion 3 which is wider, the additional width being on the rear side or toward the seat.

The sides of the casing of the door above the ledge 5 is provided with grooves 6 to

receive the vertically slideable curtain 7 provided with windows 8 and preferably constructed in the manner shown by the patent to Morine No. 1,523,704 dated January 21, 1925. This curtain may be moved up and down by means of a handle 9. In order that rain may not flow into the cab, I provide a ledge 10, preferably of sheet metal, along its upper edge, and the ledge 5 of the body is preferably grooved to permit the curtain to rest on the ledge 10 of the door.

When the lower edge of the curtain is made unyielding, it is injured and torn by the door when pulled open while the curtain is resting on this inclined ledge. I have therefore provided a weatherstrip for the lower edge of the curtain which is so yielding that the door can be swung open without injuring the curtain. One construction is a tube 12 of rubber having longitudinal flange 13 adapted to be secured between the side coverings 14 of the curtain, as shown in Fig. 6, or one of the side coverings 15 may be brought around and its edge 16 sewed directly to this flange 13, as shown in Fig. 5. Or, I may use a tube 22 of rubber which is enclosed by the outer layer 23 of the curtain and held thereby centrally of the metal frame 24 of the curtain, the edge 25 of this layer 23 being covered by the inner layer 26 and held in place by the line of stitches 27 of the curtain. In each of these embodiments the outer layer of the curtain continues around the filler and extends up on the inside so that there is no outer lap to catch water. The construction of this weatherstrip may be further varied so long as it is sufficiently resilient to permit the door to be swung open or closed and pass below the weatherstrip without damaging it.

While I have described this door and curtain as adapted for truck cabs, the idea may be adapted to vehicle tops of any desired character without departing from the spirit of my invention as set forth in the following claims.

I claim:

1. In a door construction, vertical sides of a door casing having upright grooves, a flexible curtain slideable in said grooves, and a door hinged in the casing below the curtain and having its upper edge sloping downwardly outwardly and positioned so that the curtain may rest thereon, the lower

edge of said curtain being formed with a weatherstrip of material so yieldable as to permit the door to pass below the curtain without injuring the weatherstrip when the curtain is in its lowest position.

2. In a door construction, vertical sides of a door casing having upright grooves, a flexible curtain slidable in said grooves, and a door hinged in the casing below the curtain and having its upper edge sloping

downwardly outwardly and positioned so that the curtain may rest thereon, the lower edge of said curtain being formed with a weatherstrip so yieldable as to permit the door to pass below the curtain without injuring the weatherstrip when the curtain is in its lowest position, and said weatherstrip consisting of a flexible tube of rubber.

FREDERICK D. RITTER.
